UNITED STATES PATENT OFFICE.

JOHN HAYS HAMMOND, JR., OF GLOUCESTER, MASSACHUSETTS.

THERMOSTAT CONTROL FOR COOKING UTENSILS.

Application filed December 19, 1923. Serial No. 681,544.

It is an object of this invention to provide means for automatically controlling the temperature of the contents of a cooking utensil so that when the temperature has reached a certain predetermined degree the supply of heat will be shut off so as to prevent any increasing in temperature of the contents of the cooking utensil.

Other objects will appear from the following description taken in connection with the accompanying drawings, in which

Figure 1 is a top plan view of a mechanism constructed in accordance with this invention. Fig. 2 is a front elevation of same, and Fig. 3 a side elevation of the same. Fig. 4 is a rear elevation; Fig. 5 a modified form of the invention; Fig. 6 is another modified form of the invention; Fig. 7 still another modified form of the invention and Fig. 8 a modification of part of the mechanism shown in Fig. 7.

Referring to the accompanying drawings, and particularly in Figs. 1 to 4 inclusive, the invention as shown consists of a base 10 provided with a plurality of vanes 11 each pivoted so as to be rotatable about an axis extending substantially longitudinally thereof, and rigidly connected at one end to an arm 12. The vanes 11 may be covered with any suitable heat insulating material such as, for example, asbestos. The arms 12 are pivotally secured to a connecting link 13 which is provided with a pin 14 which slides in a slot 15 of an actuating arm 16. The arm 16 is pivoted at 17 to a slider 18 which slides in a slot 19 provided in an upright member 20. The slider 18 is provided with a mark which co-operates with graduations 21 for indicating the position of the slider 18. The slider 18 engages a screw 22 which is turned by a knurled head 23. The upper end of the arm 16 is provided with a slot 25 which engages the end of a second arm 26 pivoted at 27 to a member 28 which is hinged to the member 20 at points 29 and 30. This hinge is so arranged that when the member 28 is rotated the end of the arm 26 will remain in the slot 25. The inner end of the member 28 is bent as shown in Fig. 3 and has secured to it a piece of flexible material 32, to the outer part of which is secured the cover 33, which fits upon the container 34. By the use of the flexible strip 32 it is possible for the cover 33 to fit snugly upon the top of cooking utensils of various heights. The inner end of

the arm 26 is provided with a slot 35 which engages a rod 40, the lower end of which is secured to a member 41 composed of two dissimilar substances having different coefficients of expansion riveted together. This member is rigidly secured at the lower end by a bracket 42 to an upright plate 43 which is rigidly connected to the member 28. The pin 44 is provided in the plate 43 to prevent the member 41 from moving beyond a certain desired position.

In the operation of the form of the invention shown in Figs. 1 to 4 inclusive, the substance to be heated is placed in the container 34 and cover 33 is placed thereon. The base 10 is set over a suitable burner, the heat from which passes up between the vanes 11, as shown in Fig. 2 striking upon the bottom of the container 34, thus heating its contents. As the temperature increases the member 41 being made of two dissimilar materials will be flexed thus moving the rod 40 to the right as seen in Fig. 4. This rotates the arm 26 in a counter clockwise direction as seen in Fig. 1 which in turn rotates the arm 16 about the pivot 17 in a clock-wise direction as seen in Fig. 2. This causes the link 13 to be moved to the left, thus rotating the arms 12 and the vanes 11 in a counter clockwise direction as seen in Fig. 2. As the temperature of the substance increases this motion continues until, when the substance is at the predetermined temperature the link 13 will be moved to its extreme position, thus causing the vanes 11 to be turned in a horizontal position, thus cutting off the supply of heat from the under surface of the container 34. If the temperature of the contents decreases the reverse action will take place and the vanes 11 will be rotated in a clockwise direction, thus allowing more heat to reach the container 34. The temperature at which the heat is shut off can be varied by turning the thumb screw 23, which by means of the slider 18 will change the relative position of the pivot point 17 so that the vanes 11 may be closed at a lower or higher temperature depending upon which direction the slider 18 is moved. The graduations 21 are so calibrated that the operator can tell at what temperature the heat will be shut off.

In the form of the invention shown in Fig. 5 the link 13 is operated by a lever 51 pivoted at 52 to the support 20. This lever is held in the position shown by means of a

spring 53. The upper end of the lever 51 is provided with a notch 54 which at suitable times is engaged by the arm 26. The arm 26 is operated by the expansion member 51 as described in connection with Figs. 1 to 4. A colored ball 56 is secured to an arm 57 which is attached to the arm 12.

In the operation of the modified form of the invention shown in Fig. 5 when the 10 contents of the container 34 has reached a predetermined temperature the end of the lever 26 will engage the notch 54 in the arm 51, and as the temperature increases it will cause the arm 51 to be rotated in a clockwise direction about the pivot 52, thus rotating the vanes so as to shut off the supply of heat to the container 34. As the contents cool down the lever 26 moves to the left as seen in Fig. 5 the arm 51 will rotate in a counter 20 clockwise direction by the action of the spring 53 and will open the vanes so as to allow more heat to strike the container 34. The colored ball 56 serves to indicate to the operator when the contents of the container 25 34 have reached the required temperature.

In the modified form of the invention shown in Fig. 6 the link 13 is provided with a projection 61 which normally engages a rod 62 slidably mounted in a bearing 63 and 30 connected at its upper end to a bell-crank 64 which is held in the position shown by a spring 65 and is pivoted about the points 66. At suitable times the lever 26 engages the upper ends of the bell-crank 64. To the 35 right-hand end of the link 13 is screwed a handle 67 to which is attached one end of a spring 68, the other end of which is secured to the upright 20. At the left-hand of the link 13 is a small projection 70 which at the 40 proper time strikes a bell 71 secured to the base 10.

In the operation of the form of the invention shown in Fig. 6 when the contents of the container 34 has reached the proper temperature 45 the arm 26 is moved to the right as described in connection with Figs. 1 to 4 and engages the upper end of the bell-crank 64, rotating it in a clockwise direction, thus lifting the rod 62 until it moves out of engagement with a projection 61, thus allowing the link 13 to be moved to the left under the action of the spring 68 which causes the vanes to be closed, thus shutting off the supply of heat from the container 34, and at the 55 same time the projection 70 will strike the bell 71, thus giving an audible indication that the contents of the container 34 has reached the proper temperature.

In the modified form of the invention 60 shown in Fig. 7 the arm 12 is connected by a link 75 to a lever 76, pivoted at 77 on a sliding member 78 which slides in a groove 79 provided in the bracket 80. The sliding member 77 is moved by a screw 81 which is 65 turned by the knurled head 82. Graduations

83 are provided on bracket 80. The upper end of the lever 76 is connected to a rod 85, the other end of which is screwed to a flexible membrane 86 made of any suitable material such as soft leather. This membrane 70 covers an opening of a container 87 which is connected by a tube 88 to a second container 89 which is placed in the contents of the container 34. Containers 87, 89 and the pipe 88 are filled with a suitable fluid which 75 has a large coefficient of expansion.

In the operation of the form of the invention shown in Fig. 7 as the contents of the container 34 increase in temperature, the 80 contents of the container 89 will also increase in temperature and will at the same time increase its volume, thus forcing the flexible membrane 86 outward, which in turn will move the rod 85 to the left, thus rotating the lever 76 in a counter clock-wise direction 85 about the pivot 77 which by means of the link 75 will rotate the arms 12, thus closing the vanes and shutting off the supply of heat from the container 34. If the temperature of the contents of the container 34 decreases, 90 the reverse action will take place and the vanes will be opened. By adjusting the position of the slider 78, by means of the knurled head 82 the temperature at which the vanes will close can be varied. 95

In Fig. 8 is shown a modified form for adjusting the temperature at which these vanes will close. In this form of the invention the chamber 87 is provided with a secondary membrane 91 which is pressed inwardly by a screw 92 threaded in a bracket 93 and provided with a knurled head 94. By turning the knurled head 94 the volume of the chamber 87 can be changed so that the temperature at which the vanes will be 105 closed can be varied at will.

What I claim is:—

1. In a cooking utensil, the combination of a vessel, an element positioned therein responsive to variations in temperature, a source of heat spaced from the vessel, a plurality of movable vanes each including a layer formed of heat insulating material interposed between the vessel and the heat source to control the temperature of the vessel between predetermined temperature limits, and means operatively interconnecting said element and said vanes. 115

2. In a cooking utensil, the combination of a vessel, an element positioned therein responsive to variations in temperature, a source of heat spaced from the vessel, a plurality of movable vanes each including a layer formed of heat insulating material interposed between the vessel and the heat source to control the temperature of the vessel, and means operatively interconnecting said element and said vanes. 120

3. In a cooking device comprising a utensil, a cover for said utensil having an aper- 125

- ture and a heat responsive element depending through said aperture and into the interior of the utensil, a source of heat spaced from the utensil, a plurality of rotatable shutters each having a covering formed of heat insulating material positioned between the heat source and the utensil, a connecting link for causing the simultaneous actuation of said shutters, and means operatively interconnecting said connecting link and said heat responsive element to control the movement of the shutters.
4. In a cooking device, the combination with a vessel and a cover therefor, of a flexible heat responsive element depending from the cover into the interior of the vessel, a source of heat spaced from the vessel, a plurality of shutters each including at least a layer of asbestos and positioned between the heat source and the vessel arranged in one position to screen the vessel from the heat source and movable from said position to permit heat to be applied from said source to the vessel, and an arm interconnecting said shutters and said heat responsive element to impart the movement of said heat responsive element to said shutters.
5. In a cooking device, the combination of a vessel, an element positioned therein responsive to variations in temperature, a source of heat spaced from the vessel, a plurality of shutters each including a layer formed of heat insulating material pivotally mounted between the vessel and the heat source to control the temperature of the vessel between desired temperature limits, means operatively interconnecting said element and said shutters, and means to modify the action of said heat responsive element upon said shutters.
- 40

In testimony whereof I hereunto affix my signature.
